ALBERT SCHMID, OF LONG BEACH, AND LAWRENCE AUGUST MERK, OF NEW YORK, N. Y.;
SAID MERK ASSIGNOR TO SAID SCHMID.

CARBURETER.

1,325,999.

Specification of Letters Patent. Patented Dec. 23, 1919.

Application filed June 12, 1918. Serial No. 239,687.

To all whom it may concern:

Be it known that we, ALBERT SCHMID and LAWRENCE AUGUST MERK, citizens of the United States, and residents of Long Beach, 5 L. I., and New York city, N. Y., respectively, have made a new and useful Invention in Carbureters, of which the following is a specification.

This invention relates to charge forming 10 devices for internal combustion engines, and more particularly to two fuel charge forming devices or carbureters.

It is now customary to provide carbureters operating on two fuels, one readily 15 inflammable such as gasolene and one not readily inflammable such as kerosene. The readily inflammable fuel is used for starting and warming up and when the engine and the inlet manifold is sufficiently warm 20 to care for charges of the not readily inflammable fuel the readily inflammable fuel supply is cut out and the other cut in. It has been proposed to do this cutting in and cutting out automatically and we therefore 25 make no claim to this broadly.

We have found that in using kerosene and other not readily inflammable fuels to obtain smokeless operation the combustible mixture must enter the cylinders of the engine 30 at a relatively high temperature when running at light loads or torques. We have also found that to prevent spontaneous combustion in the cylinders when operating on heavy loads or heavy torques the combustible mixture should enter the cylinders 35 at the lowest possible temperature consistent with smokeless operation and this same requirement prevails for obtaining maximum output of a given engine. It has been here- 40 tofore proposed to pass all or a part of the exhaust gases through a heating chamber surrounding the carbureter for the purpose of heating the same and it has further been proposed to control the flow of exhaust 45 gases through this heating chamber by means of a valve connected up to the throttle valve of the carbureter so as to operate in synchronism therewith. We have found, however, that by operating this valve in the 50 by-pass around the heating chamber by means dependent upon the pressure or vacuum in the engine inlet manifold a much more satisfactory operation can be obtained and we have found that by controlling and 55 operating the mechanism for shifting from

one fuel to the other automatically by means of a thermostatic device subjected to the temperatures of the carbureter operating in conjunction with the device for automatically controlling the flow of exhaust gases 60 through the carbureter heating chamber in accordance with the pressure or vacuum in the engine inlet manifold we are enabled to provide a device by means of which an engine may be quickly and readily started and 65 operated through all of its varying loads without smoke or objectionable deposits.

An object of this invention is to provide in a two fuel charge forming device in conjunction with means for automatically cutting in one fuel and cutting out the other and vice versa, means operating in accordance with the changes in pressure in the engine inlet manifold for regulating the temperature of the charge forming device. 75

A further object is to provide means for visibly indicating the time of change from one fuel to the other.

These, as well as other objects which will readily appear to those skilled in this art, 80 we attain by means of the device illustrated in the drawings accompanying and forming a part of this application.

In the drawings Figure 1 is a more or less diagrammatic view partially in section and 85 partially in elevation of a device or system embodying this invention and Fig. 2 is a diagrammatic view of the means for visibly indicating the time of change from one fuel to the other in the system. The device 90 primarily consists of a carbureter having a fuel nozzle 3 alternately supplied with fuel from float chambers 4 and 5, an air inlet 6 controlled by means of a valve 7, a Venturi choke tube 8 and a mixture passage 9 95 connected with the inlet manifold 10 of an internal combustion engine and controlled by means of a throttle valve 11 which through lever 12 and suitable connections is under the control of the engine operator. 100

A supplemental air valve 13 admits supplemental air to mixture passage 9.

Float chamber 4 by means of a suitable pipe 14 is connected up to a source of kerosene supply not shown while float chamber 5 by means of a pipe 15 is connected up to a source of supply of gasolene not shown. The effective area of fuel nozzle 3 is controlled by means of a needle valve 16.

The outlet 17 of float chamber 4 is con- 110

trolled by means of a needle valve 18 mounted on a piston 19 slideable in a bore formed for its reception within the base portion of the carbureter. A spring 20 surrounds 5 rounding the stem of the needle valve tends to yieldingly hold the same from its seat.

Outlet 21 from float chamber 5 is controlled by means of a needle valve 22 carried on a plunger 23 slideable in a bore formed 10 for its reception in an upright extension of the carbureter base. A spring 24 surrounds stem of needle valve 22 and tends to yieldingly force it from its seat.

A rocking lever 26 pivoted to the body of 15 the carbureter at 27 is provided with cupped ends 28 and 29 which stand in line with the upper ends of valves 18 and 22 so that as one valve is depressed and seated the other valve will be unseated by its spring. One arm of 20 lever 26 is connected to a lever 30 by means of a connecting link 32. Lever 30 is pivoted to the carbureter body at 31. A spring 33 secured to the carbureter body at 34 connects with the upper end of connecting link 25 32 and tends to close valve 22. A lever 35 pivoted to the carbureter body bears against an adjustment pin 36 carried by lever 30 and between lever 35 and an abutment lug 37 a quartz rod 38 is positioned. This quartz rod 30 with the carbureter body and the levers and links forms the thermostatic device for automatically controlling and operating the 25 two fuel valves.

Lever 26 is connected up to one side of a 35 battery 39 by means of line 40 and contact member 43 is connected up to the other side of the battery by means of line 41 in which a switch 42 is interposed. Line 41 is provided with a contact member 43 and lever 26 is 40 provided with a contact member 44. A bulb 45 positioned at some convenient place within the vision of the operator will, provided switch 42 is closed, glow when valve 22 is opened thus visibly indicating the time during 45 which gasoline is being used. As soon as valve 22 is closed the connection between contacts 43 and 44 will be broken. Since the time when gasoline is being used is shorter than the time when kerosene is being 50 used it is preferable, although not necessary, to have lamp 45 indicate by glowing when valve 22 is opened.

A jacket 50 surrounds the major portion of the carbureter and provides a heating 55 chamber 51 connected up to the exhaust manifold 52 of the engine by means of an exhaust pipe 53. Heating chamber 51 also connects with exhaust pipe 54 from the engine by means of a pipe 55. Exhaust pipe 60 54 is provided with a valve device for controlling its effective area and this device consists of a balanced valve 56 the stem 57 of which connects with a piston 58 mounted for reciprocation in a cylinder 59. End 65 60 of said cylinder is open to atmospheric

pressure through a port 61 and end 62 is subjected to the pressure within inlet manifold 10 through a pipe connection 63. A spring 64 located in end 62 of cylinder 59 tends to yieldingly hold valve 56 open while 70 atmospheric pressure entering through port 61 when the pressure within the inlet manifold is below atmospheric pressure tends to close valve 56.

During light loads and when starting, 75 throttle valve 11 will be nearly closed and therefore valve 56 will be closed owing to the difference between atmospheric pressure and the pressure or the vacuum within the inlet manifold and all of the exhaust gases will 80 pass through pipe 53 and heating chamber 51. As the throttle 11 is opened the pressure in the inlet manifold will increase and valve 56 by means of spring 64 will be partially opened thereby passing a portion of the exhaust 85 gases around heating chamber 51. In starting when the carbureter is cold, gasoline will be admitted as the fuel and the exhaust gases will quickly heat the carbureter and when hot the gasoline will be shut off. After 90 having once started on gasoline the gasoline will merely come into occasional use as the carbureter in itself will store considerable heat, sufficient to vaporize the heavy fuel and the hot carbureter will keep the ther- 95 mostatic device from shifting from heavy to light fuel.

It has been found in actual use that after the engine has been started on gasoline it rarely comes into use again until after a long 100 period of rest. Valve 56 controls the heat so that during widely varying loads the carbureter is maintained at a temperature sufficient to care for the heavy fuel.

Having thus described our invention, 105 what we claim is—

1. In a charge forming device for internal combustion engines, means for alternately supplying the same with different liquid fuels and means for indicating the change 110 from one to the other of said fuels.

2. In a charge forming device for internal combustion engines, means for alternately supplying same with different liquid fuels and means for visibly indicating the 115 change from one to the other of said fuels.

3. In a charge forming device for internal combustion engines, means for alternately supplying the same with different liquid fuels and means operated electrically for 120 visibly indicating the change from one to the other of said fuels.

4. In a charge forming device for internal combustion engines, heating means for said device, a remotely located indicator and 125 thermostatically operated means for controlling said indicator so as to indicate changes in temperature of said device above and below a predetermined point.

5. In a charge forming device for internal 130

combustion engines, means for supplying the same with different liquid fuels and a thermostatically controlled switch for cutting in or out visible indicating means as the temperature of said device increases or decreases from a determined point.

6. In a charge forming device for internal combustion engines, thermostatically operated means for alternately supplying the same with different fuels, means for heating said device by exhaust gases and means for automatically controlling the supply of exhaust gases to said device.

7. In a charge forming device for internal combustion engines, thermostatically operated means for automatically and alternately supplying the same with different fuels, means for heating said device by exhaust gases and means for automatically controlling the supply of such exhaust gases.

8. In a charge forming device for internal combustion engines, means including a thermostatic device for alternately supplying the same with different fuels, means for heating said device by exhaust gases and means dependent upon the pressure in the engine inlet manifold for controlling the supply of exhaust gases to said device.

9. In a charge forming device for internal combustion engines, thermostatically operated means for alternately supplying the same with different fuels, means for heating said device by exhaust gases and means the operation of which is dependent upon the pressure in the engine inlet manifold for automatically controlling the supply of exhaust gases to said device.

10. A charge forming device for internal combustion engines having means including a thermostat for alternately supplying the same with different liquid fluids, characterized in that one element of the thermostat

is formed by the body of the charge forming device while the other element thereof is supported from the body and formed of material having a different expansion co-efficient than the material from which the body is formed.

11. In combination with a charge forming device for internal combustion engines having means for heating said device, visible indicating means and means operating upon variations in the temperature of said device for controlling the operation of said indicating means.

12. In combination with a charge forming device for internal combustion engines, means for heating the same with exhaust gases, indicating means and means responsive to variations in the temperature of said device for controlling the operation of said indicating means.

13. In combination with a charge forming device for internal combustion engines, means for heating the same, indicating means remotely located with reference to said device and means responsive to variations of the temperature in said device for controlling the operation of said indicating means.

14. In a charge forming device for internal combustion engines, thermostatically operated means for alternately supplying the same with different fuels, a heating chamber for said device, a conduit for leading exhaust gases through said chamber, a conduit for by-passing exhaust gases around said chamber, a valve in said latter conduit, and means for controlling said valve.

In testimony whereof, we have hereunto subscribed our names this 5th day of June, 1918.

ALBERT SCHMID.
LAWRENCE AUGUST MERK.
